UNITED STATES PATENT OFFICE.

CARL A. JONES, OF BRISTOL, VIRGINIA.

DESIGN FOR A BOTTLE.

Application filed December 4, 1925. Serial No. 15,634. Term of patent 14 years.

To all whom it may concern:

Be it known that I, CARL A. JONES, a citizen of the United States, residing at Bristol, Virginia, in the county of Washington, have invented a new, original, and ornamental Design for Bottles, of which the following is a specification, reference being had to the accompanying drawing, forming a part thereof.

The figure is a side view in elevation of a bottle, showing my new design.

I claim;

The ornamental design for a bottle, as shown.

CARL A. JONES.
